COMBUSTION PRODUCTS DETECTOR

Norbert Thomas Wolfe, Minneapolis, Minn., assignor to
Honeywell Inc., Minneapolis, Minn., a corporation of
Delaware

Filed July 17, 1967, Ser. No. 7,826

Term of patent 14 years

(Cl. D72—1)

FIG. 1

FIG. 2

FIG. 3

FIGURE 1 is a top plan view of a combustion products detector showing my new design;

FIGURE 2 is an elevational view taken from the side thereof; and

FIGURE 3 is a partial cross sectional view of FIGURE 1 taken on line 3—3 thereof.

The dominant features of my design reside in the portions shown in full lines.

I claim:

The ornamental design for a combustion products detector, substantially as shown and described.
